(No Model.)

A. H. TITUS.

PUMP.

No. 448,282.

Patented Mar. 17, 1891.

UNITED STATES PATENT OFFICE.

ABRAHAM H. TITUS, OF DARNALL, NEBRASKA.

PUMP.

SPECIFICATION forming part of Letters Patent No. 448,282, dated March 17, 1891.

Application filed August 6, 1890. Serial No. 361,212. (No model.)

To all whom it may concern:

Be it known that I, ABRAHAM H. TITUS, a citizen of the United States, residing at Darnall, in the county of Keya Paha and State of Nebraska, have invented certain new and useful Improvements in Pumps; and I do hereby declare the following to be a full, clear, and exact description of the invention, such as will enable others skilled in the art to which it appertains to make and use the same.

This invention has relation to improvements in pumps; and it has for its object to provide a double-acting lift or force pump, whereby a greater amount of water is drawn or forced out, all as will be hereinafter more particularly pointed out.

The annexed drawings, to which reference is made, fully illustrate my invention, in which—

20 Figure 1 represents a side view of my improved pump, partly in section. Fig. 2 is a sectional view of the cap, and Fig. 3 is a plan view of the same. Fig. 4 is a detail view of the valve enlarged.

25 Referring by letter to the accompanying drawings, A designates the pump, and a is the stock or tube, at the lower end of which is an enlarged cylinder b, in which the plunger c of the piston-rod d has its vertical play.

30 Connected to this cylinder is a cylinder e, which communicates with the cylinder b, as at f, and above the plungers. Within this cylinder e is a plunger g. The rod h thereof is passed through a cap i, having a packing 35 and connected to the lower end of a rod j by a joint connection k. This rod h passes through a guide-bar l, secured to the pipe or tubing and serves to guide said rod in its vertical movement.

40 B represents a standard secured to the top of the pump, to which a double-cranked handle m is journaled, as at n. This crank-shaft has swiveled to it at o p the upper ends of the two rods, one of which passes down 45 through the pump and the other is on the outside thereof and passes through a guide-slot q in the rim or base r of said pump.

C indicates a cap, which is attached to the top of the pump. Through the top of

said cap is provided a slot s, through which 50 passes the rod d, and a housing t is secured to this top or cap, having a slot u, corresponding with the slot in the cap and arranged in line and above the same. This housing forms a guideway for a sliding plate 55 v, which has an opening w, through which said rod also passes. The lower end of the two cylinders aforesaid are provided with removable valve-boxes x x, (shown enlarged in Fig. 4 of the drawings,) which are provided 60 with strainery y, whereby sediment or gravel is prevented from entering the pump. This valve-box x has an upper and lower collar or flange a' on its inner side, having central openings b' b', and the strainery are bolted to 65 the lower collar by bolts c' e' between said collar and a ring d', the bolt e' serving the double purpose of holding the valve f' in place as well as fastening the screen or strainer.

Having thus described the different parts 70 of which my device is composed, I will now explain its operation. The operator in drawing water simply grasps the handle z of the crank-shaft and revolves it, thus revolving the cranks at the same time the plungers and their rods are 75 vertically operated alternately, and by means of the second cylinder e a constant stream of water is supplied to the tubing a, the water passing out of the spout a' in the usual manner. The object of the sliding plate, which at all 80 times covers the slot in the cap, is to prevent the water from coming out of the top of the pump. It will thus be seen that I provide a double-acting pump which gives great force to the water, and it is easily operated, durable, and 85 at the same time cheap to manufacture.

I am aware that a force-pump has been constructed prior to my invention in which there has been combined two cylinders, two tubes provided with tubes within said cylinders, a 90 valve-controlled receiving-chamber, a tube extending upwardly from said chamber, a beam fulerumed in a support on the upper end of said tube, and detachable rods, one of which is extended above the beam for connection 95 with a wind-wheel, whereby the pump may be made either double-acting or single-acting and the opposite sides be operated either by the

same power, or one by hand and the other by wind-wheel, and I do not claim said construction herein.

What I claim is—

- 5 In a double-acting cylinder-pump, the combination, with a cylinder provided at its lower end with a removable valve-box provided with a strainer, of an upper or lower collar or flange on its inner side, the strainer being bolted to the lower collar between a ring d' and said

collar, the bolt e' of the pair of bolts serving the double purpose of holding the valve in place and fastening the screen or strainer, substantially as specified.

In testimony whereof I affix my signature in presence of two witnesses.

ABRAHAM H. TITUS.

Witnesses:

CHAS. E. LEAR,
LEWIS L. MILLARD.
